UNITED STATES PATENT OFFICE.

PATRICK J. MADDEN, OF CHICAGO, ILLINOIS.

DESIGN FOR A WASHBASIN.

SPECIFICATION forming part of Design No. 36,127, dated October 28, 1902.

Application filed January 8, 1902. Serial No. 88,946. Term of patent 7 years.

To all whom it may concern:

Be it known that I, PATRICK J. MADDEN, a citizen of the United States, residing at Chicago, in the county of Cook and State of Illinois, have invented and produced a new, original, and ornamental Design for a Washbasin, of which the following is a full, clear, and exact description, reference being had to the accompanying drawings, which are made a part hereof, and in which—

Figure 1 is a plan view of a washbasin of the new design. Figs. 2 and 3 are vertical sections thereof on the lines 2 2 and 3 3, respectively, Fig. 1.

One of the leading features of the new design is the shape or contour of the front wall of the basin, which, as indicated by dotted lines in Fig. 1, describes a double compound curve or a double ogee *a b a*, with the convexity of the intermediate portion *b* presented inward with respect to the basin and of substantially the same sweep or radius as the portion *a*, said intermediate portion being substantially parallel with the rear wall *c*.

Another leading feature of the new design is the shape or outline of all the walls, including the front wall of the above-described double-ogee shape, the curved rear wall *c* describing a continuous sweep from end to end and the curved end walls *d d* gradually merging with the front and rear walls.

Another leading feature of the new design is the slab *e*, having an opening corresponding in outline with the above-described outline of the walls of the basin.

35

Another feature of the new design is the approximate concentricity of the rear wall *c* and the middle portion *b* of the front wall and the end walls *d*, following curves that merge with the curves of the front and rear walls.

40

A minor feature is the bead *e'*, which follows the above-described contour of the front wall of the basin and meets the slab *e* at the ends of the basin.

Another minor feature is the angular shape 45 of the rear side of the slab, said rear side being bounded by two straight lines meeting at right angles.

Another minor feature of the invention is the gradual slope of the front wall *b* and bottom *f* toward the back *c*, the latter being vertical, and the slope of the end walls *d* toward each other.

What I claim is—

The ornamental design for a washbasin, 55 substantially as herein shown and described.

PATRICK J. MADDEN.
